(57) **CLAIM**

The ornamental design for a writing implement as shown and described.

DESCRIPTION

FIG. 1 is a perspective view of a first embodiment of a writing implement, showing the body in isolation, in accordance with our design;

FIG. 2 is a perspective view thereof showing end caps in a first, removed position;

FIG. 3 is an end view of the first embodiment of the writing implement shown in FIG. 1, which is identical for both ends;

FIG. 4 is a top plan view showing the body in isolation thereof;

FIG. 5 is a bottom plan view showing the body in isolation thereof;

FIG. 6 is a perspective view thereof showing end caps in a second, installed position;

FIG. 7 is a perspective view of the end cap shown in isolation, taken toward a first end of one of the end caps shown in FIGS. 2 and 6;

FIG. 8 is an end view of the end cap shown in isolation of the first end of the end cap shown in FIG. 7;

FIG. 9 is an end view of a second end of the end cap shown in FIG. 7;

FIG. 10 is a right side elevational view of the end cap shown in isolation in FIG. 7;

FIG. 11 is a bottom plan view of the end cap shown in isolation in FIG. 7;

FIG. 12 is a left side elevational view of the end cap shown in isolation in FIG. 7;

FIG. 13 is a perspective view taken toward the second end of the end cap shown in isolation in FIG. 7;

FIG. 14 is a perspective view of a second embodiment of a writing implement, showing the body in isolation, in accordance with our design;

FIG. 15 is an exploded perspective view thereof showing end caps in a first, removed position;

(Continued)

FIG. 16 is an end view of the second embodiment of the writing implement shown in FIG. 14, which is identical for both ends;

FIG. 17 is a top plan view of the second embodiment of the writing implement showing the body in isolation thereof; FIG. 18 is a bottom plan view of the second embodiment of the writing implement showing the body in isolation thereof; FIG. 19 is a perspective view thereof showing end caps in a second, installed position;

FIG. 20 is a perspective view of the end cap in isolation, taken toward a first end of one of the end caps shown in FIGS. 15 and 19;

FIG. 21 is an end view of the first end of the end cap shown in FIG. 20;

FIG. 22 is an end view of a second end of the end cap shown in isolation in FIG. 20;

FIG. 23 is a right side elevational view of the end cap shown in isolation in FIG. 20;

FIG. 24 is a bottom plan view of the end cap shown in isolation in FIG. 20; and,

FIG. 25 is a left side elevational view of the end cap shown in isolation in FIG. 20.

The broken lines shown in the drawings represent portions of the writing implement that form no part of the claimed design.

The claim is directed to the collective appearance of all elements shown.

1 Claim, 25 Drawing Sheets
